TETRAHEDRAL CONTAINER

Ralph E. Dykes, Saddle Brook, N.J., and Robert M. Mitchell, South Norwalk, Conn., assignors to General Foods Corporation, White Plains, N.Y., a corporation of Delaware

Filed June 24, 1963, Ser. No. 75,501

Term of patent 14 years

(Cl. D58—2)

FIG. 1 is a perspective view of a tetrahedral container, showing our new design;

FIG. 2 is a perspective thereof;

FIG. 3 is an elevational view thereof;

FIG. 4 is an elevational view thereof rotated 90° clockwise from the position in FIG. 3;

FIG. 5 is an elevational view thereof rotated 90° clockwise from the position in FIG. 4; and

FIG. 6 is an elevational view thereof rotated 90° clockwise from the position in FIG. 5.

The characteristic feature of the design resides in the combination on the tetrahedral container disclosed of the arrangement of the four faces, each of which is a right triangle, two adjacent ones of which have the same area

and a common hypotenuse, the other two faces not having a common hypotenuse, substantially as shown.

We claim:

The ornamental design for a tetrahedral container, substantially as shown and described.
